US00D382182S

United States Patent [19]

Seber et al.

[11] Patent Number: Des. 382,182

[45] Date of Patent: **Aug. 12, 1997

[54] COMBINATION TOOL

1,474,592 11/1923 Jacoby .

[75] Inventors: **Brett P. Seber**, Escondido; **Randolph J. Morton**, Coronado; **Gabriel Alejandro Dragucevich**, Solana Beach; **Lonnie C. Pogue**, San Diego, all of Calif.

(List continued on next page.)

[73] Assignee: **Buck Knives, Inc.**, El Cajon, Calif.

[**] Term: 14 Years

[21] Appl. No.: 48,866

[22] Filed: Jan. 11, 1996

[51] LOC (6) Cl. 08-05

[52] U.S. Cl. D8/55; D8/105

[58] Field of Search D8/51, 52, 54, D8/55, 105; 7/118, 129, 168, 125, 128, 127, 167

[57] CLAIM

The ornamental design for a combination tool, as shown and described.

DESCRIPTION

FIG. 1 is a left-side elevational view of a combination tool with the handles in the nested position, the right-side elevational view being identical thereto;

FIG. 2 is a top view thereof, the bottom view being identical thereto;

FIG. 3 is a left-end elevational view thereof;

FIG. 4 is a right-end elevational view thereof;

FIG. 5 is a left-side elevational view of the combination tool with the handles in the fully deployed position, the right-side elevational view being identical thereto;

FIG. 6 is a top view thereof, the bottom view being identical thereto;

FIG. 7 is a left-end elevational view thereof;

FIG. 8 is a right-end elevational view thereof;

FIG. 9 is a left-side elevational view of the combination tool with the handles in the semi-deployed position;

FIG. 10 is a right-side elevational view thereof;

FIG. 11 is a top view thereof;

FIG. 12 is a bottom view thereof;

FIG. 13 is a left-end elevational view thereof; and,

FIG. 14 is a right-end elevational view thereof.
